SYSTEM OF METAL SHELVES DISPLACEABLE FOR BOOKCASES AND SIMILAR ARTICLES

Auguste Hubert Liesken, Brussels, Belgium

Application January 6, 1938, Serial No. 183,729
In Belgium June 1, 1937

4 Claims. (Cl. 248—243)

The present invention relates to metal shelves displaceable on racks provided on vertical supports, which are particularly suitable for bookcases or similar articles.

- 5 The object of the invention is to provide displaceable shelves of the type described above, which can be removably fixed to the supports simply and firmly and in a manner giving complete security against accidental displacement.
- 10 10 The invention also provides for the easy displacement of these shelves along their support substantially parallel to their plane and of their easy removal.

For this purpose the invention provides that the 15 said shelves which are engaged in the above mentioned racks are also locked locally against an element, for example, a face of the vertical supports which is situated in a plane other than that of the racks.

20 20 The invention also provides for the locking of the shelves by means of lugs which are preferably disposed at right angles to the vertical supports and cooperate with recesses provided in the above mentioned element of the vertical supports.

25 25 The invention provides also that when the shelves are displaced substantially parallel to their plane the amplitude of their forward tilting movement shall be limited to a predetermined value in order to prevent the books which they 30 carry from sliding and falling off them. The amplitude may be limited by a bolt arrangement which is rigidly fixed to the vertical sides of the shelves and which in the closing position is locked against the wings of the uprights of the article.

35 35 The invention relates also to other features which will appear in the following description.

The attached drawings show by way of example one embodiment of the invention. The latter covers the various original features comprised in 40 the arrangement shown.

Fig. 1 is an elevation of the set of shelves according to the invention showing the arrangement limiting the rocking of the shelves.

45 45 Fig. 1a is a view similar to Fig. 1, showing a displaceable shelf in the tilted position.

Fig. 2 is a plan of the support with a section of the upright, the support being mounted in position.

50 50 Fig. 3 is a section of one of the vertical sides of a shelf.

Fig. 4 is a section on the line A—A of Fig. 3.

Fig. 5 is a front view of the support showing the way in which the shelf is mounted on the supports without the use of screws, screwed bolts 55

or sliding bolts which necessitate the use of tools for fixing or removing the shelves.

Fig. 6 is a diagrammatical view illustrating the manner in which the support is removed from the upright without vertical displacement. 5

Figs. 7 and 8 are a front and side view of a detail of the shelves according to the invention.

The displaceable shelves which from the subject of the present invention are on the one hand mounted by means of a pin 2 in racks 3 provided in the side wings 4 of the vertical supports 5 of the case and on the other hand locked by the cooperation of tongues 6 with slots 7 provided in the channel 8 of the vertical supports (see Figs. 1, 1a and 2). The slot is provided at the bottom of 15 a stamped portion forming a vertical guiding member for registering the tongues and the pin with their associated holes or recesses.

This very simple and at the same time very original construction enables, as will readily be 20 seen, a firm engagement of the shelves with their support to be obtained which engagement, owing to the fact that it is based upon the formation of a couple, increased with the load applied to the displaceable shelves. 25

When the shelf is in the position of Fig. 1 and it is required to move it either upwards or downwards it is first rocked forwards (see arrow) to an angle of approximately 4° to the horizontal. This rocking disengages the pin 2 from the teeth 30 of the racks 3 and also disengages the tongues 6 from the slots 7 provided in the side 8 of the vertical supports. The shelves are thus released and may be moved upwards or downwards while remaining parallel to themselves since they are 35 guided in their displacement by the flanges 9 (see Fig. 2).

When the shelves have reached the desired height it is sufficient to release them in order that the action of the couple due to their own weight 40 and that of the load may come automatically into effect and cause them to be engaged and locked with their vertical supports.

It should be noted that the rocking of the shelves preceding their displacement takes place 45 (see Fig. 1a) about an imaginary centre of rotation situated approximately at A. Owing to the presence of the radius 10 which is provided on the upper edge of the sides 12 of the shelves, the imaginary centre of rotation A is displaced downwards which allows the angle necessary for disengagement to be reduced to 4°.

In order that the books which line the horizontal face 13 of the shelves shall not slide off, it is necessary that the rocking of the shelves should 55

not exceed a predetermined value, 4° for example. For this purpose each of the vertical sides of the shelf is provided with a bolt 22 ending in a pin 23 which engages in a hole 24 provided in the rear wall of the platform 13 of the shelf. The position of these holes 24 (one hole near each end of the platform 13) is chosen in such a manner that when the pin 22 is engaged in these holes the upper wing 25 of the bolt is disposed in the path (see especially Fig. 4) of the side wing 4 of the vertical support 5.

If at this moment the shelf is swung forwards the amplitude of the swinging movement will be limited to 4° by the abutment of the wing 25 which in the normal position of the shelf is disposed obliquely (see Fig. 4) against the edge of the wing 4.

When it is desired to remove a shelf it is merely necessary first of all to draw the platform 13 out. The pins 23 are thus released and the bolt may be moved towards the right (Fig. 4) by reason of the slotted hole 22a so as to disengage itself from the wing 4 of the support.

By means of this arrangement the bookshelf or platform proper may be removed without it being necessary to touch the supports. The supports themselves may be removed instantaneously by simple rotation of the pin 2 in a vertical plane parallel to the face of the shelf. It is thus not necessary first of all to displace the shelves above or below the shelf which it is desired to remove nor the adjacent shelves of the neighbouring sections.

The horizontal face 13 of the shelves (Fig. 7), that is to say, the face intended for receiving the books is removably connected to the sides 12 of the shelves by the cooperation (see particularly Fig. 5) of parts 14 belonging to the sides 12 with corresponding parts 15 provided in the horizontal face 13.

In order to prevent the horizontal platform 13 becoming accidentally released from the sides 12 of the shelf the invention provides for furnishing the front wall of this platform with a small tongue 26 (Fig. 1) which engages in a notch 27 provided in the edge of each side.

By gently pulling forward the said face the tongue, by reason of its elasticity, will leave the above mentioned notch and the platform 13 may be separated from the sides.

It should further be noted that the shelves are provided with compressors 18 for keeping the books in place on the shelves. These compressors are provided with horizontal feet 19 which when the compressors rock (see arrow Fig. 8) under the weight of the books wedge themselves against the wings 20 forming the frame of the shelves.

It is evident that the invention is in no wise limited to the embodiment described merely by way of example and that it extends to any construction falling within the scope or the spirit of the following claims.

What I claim is:

1. Removable metal shelf construction for bookcases and similar furniture comprising two vertical uprights in the form of a casing partially open in front and provided on their front surface with side wings bent toward the interior of the casing, a rack system provided on said wings, a system of notches provided on the front surface of said casing, and rockable U-shaped lateral supports for supporting a shelf and positioned in said casing, the flanges of said U-shaped supports extending along two different inclined

planes, the upper part of said flanges bearing on the rear surface of said casing when the supports are in unhooked position, the lower part of said flanges bearing on the rear surface of said casing when the supports are in hooked position, each of said supports being provided at its upper part with a pivot pin adapted to co-operate with said rack system, and near its lower part with a system of tongues designed to penetrate into said notches, for effecting, concurrently with the pivot pin, the hooking of the supports to the upright.

2. Removable metal shelf construction for bookcases and similar furniture comprising two vertical uprights in the form of a casing partially open in front and provided on their front surface with side wings bent toward the interior of the casing, a rack system provided on said wings, a system of notches provided on the front surface of said casing, and rockable U-shaped lateral supports for supporting a shelf and positioned in said casing, the flanges of said U-shaped supports extending along two different inclined planes, the upper part of said flanges bearing on the rear surface of said casing when the supports are in unhooked position, the lower part of said flanges bearing on the rear surface of said casing when the supports are in hooked position, each of said supports being provided at its upper part with a pivot pin adapted to co-operate with said rack system, and near its lower part with a system of tongues designed to penetrate into said notches, for effecting, concurrently with the pivot pin, the hooking of the supports to the uprights, said supports being vertically movable relative to said uprights while in unhooked position, and means to limit the amplitude of the rocking of said supports.

3. Removable metal shelf construction for bookcases and similar furniture comprising two vertical uprights in the form of a casing partially open in front and provided on their front surface with side wings bent toward the interior of the casing, a rack system provided on said wings, a system of notches provided on the front surface of said casing, and rockable lateral supports for supporting a shelf and positioned in said casing, each of said supports being provided at its upper part with a pivot pin adapted to co-operate with said rack system and near its lower part with a system of tongues adapted to penetrate into said notches, for effecting, concurrently with the pivot pin, the hooking of the supports to the uprights, and a sliding bolt mechanism mounted on one of said supports and co-operating with the wings of said casing, to limit the amplitude of the rocking of these latter while the supports are being unhooked.

4. Removable metal shelf construction for bookcases and similar furniture comprising two vertical uprights in the form of a casing partially open in front and provided on their front surface with side wings bent toward the interior of the casing, a rack system provided on said wings, a system of notches provided on the front surface of said casing and rockable U-shaped lateral supports for supporting a shelf and positioned in said casing, the flanges of said U-shaped supports extending along two different inclined planes, the upper part of said flanges bearing on the rear surface of said casing when the supports are in unhooked position, the lower part of said flanges bearing on the rear surface of said casing when the supports are in hooked position, each of said supports being provided at

its upper part with a pivot pin adapted to co-operate with said rack system, and near its lower part with a system of tongues designed to penetrate into said notches, for effecting, concurrently with the pivot pin, the hooking of the supports to the uprights, said supports being vertically

movable relative to said uprights while in unhooked position, and means to limit the amplitude of the rocking of said supports, and means to lock the last-named means in operative position.

5

AUGUSTE HUBERT LIESKEN.
